LASTING MACHINE

John T. Lancaster, Newton, Mass., assignor to
 United Shoe Machinery Corporation, Borough
 of Flemington, N. J., a corporation of New
 Jersey

Application February 27, 1940, Serial No. 321,072

10 Claims.

(Cl. 12—8)

This invention relates to lasting machines and more particularly to machines for lasting the waist portions of shoes. The invention is herein illustrated as embodied in a manually-operated machine having a flexible lasting apron for working an upper over a last and inwardly over the last bottom and pressing it into position to adhere to an insole on the last. It is to be understood, however, that the invention, in various novel aspects, is not limited to use in a machine for lasting the waist portions of shoes nor to a machine in which the apron is manipulated by the operator.

It is an object of the present invention to provide a machine of the character above referred to having improved means for operating the apron in such a manner as to insure best results in working the waist portions of the upper into lasted relation to the insole. With this and other objects in view, the invention provides a last support upon which a last with its associated shoe materials may be positioned, an elastic lasting apron extending across the top of the forepart of the last, and means for stretching the apron heightwise of the last in a direction substantially normal to that portion of the bottom face of the last that curves upwardly toward the heel end rearwardly of the ball line and then stretching it inwardly over the bottom face of the last at each side in a direction substantially normal to the edge curvature of the last bottom in that location. In the illustrated construction this means comprises rolls at each side of the last, the rolls being mounted for bodily swinging movements about axes that extend heightwise and laterally of the last and are located adjacent one end of the last. Each roll is also mounted for free turning movement about an axis extending heightwise of the last and also for tipping movement about an axis extending laterally of the last. Each roll may thus accommodate itself to the varying lengthwise and heightwise curvatures of the opposite lateral faces of the last and thereafter may move inwardly over the bottom face of the last in a direction substantially normal to the lengthwise curvature of the edge of the last bottom while accommodating itself to the heightwise curvature of the bottom face of the last.

The invention will be better understood when considered with relation to the accompanying drawings, in which—

Fig. 1 is a view in right-hand side elevation of a machine in which the invention is embodied,

portions of the structure being broken away to show more clearly the construction thereof;

Fig. 2 is a view in front elevation of the machine shown in Fig. 1;

Fig. 3 is a plan view of the machine; and

Fig. 4 is a section on the line IV—IV of Fig. 1.

The illustrated machine comprises a base 10 upon which there are mounted a toe post 12 and a heel post 14 carrying means at their upper ends for supporting a last and shoe, the toe and heel posts being mounted for sliding movement toward and from each other in directions lengthwise of a shoe to accommodate shoes of different sizes. On the toe post is a forepart support 15 comprising a block 16 hollowed out to receive the top of the forepart of the shoe, the block 16 being preferably lined with rubber to prevent marring of the shoe upper. The block is pivotally connected at 18 to a threaded stud 20 in the toe post, the stud 20 being held against turning movement in the toe post by a key 22 carried by the stud and engaging a slot 24 in the toe post. The stud 20 and the block 16 are adjustable upwardly and downwardly by means of a knurled nut 26 which bears on the top face of the toe post 12. Plates 28 (Figs. 1 and 3), secured to the base 10 by screws 27, form with the base a guideway 29 for the toe post which may be held in any selected position in the guideway by a wing screw 30.

The heel post 14 supports a block 32 carrying a spindle 33 arranged to enter the spindle hole in the heel end of the last. As shown, the block is pivotally connected to the heel post for swinging movements about an axis extending laterally of the shoe to permit tipping movements to be imparted to the spindle in directions toward and from the forepart support 16. The heel post 14 is supported by a bushing 34 threaded in a slide 36, the bushing surrounding a downwardly extending portion 37 of the heel post and having formed on its lower end a head 38 by means of which the bushing may be rotated to vary the position of the heel post 14 and the block 32 heightwise of the shoe relatively to the forepart support. The slide 36 is horizontally movable in the guideway 29, and for thus moving the slide 36 and with it the heel post, there is provided an adjustable screw 39 which is threaded in the slide 36 and is provided at its inner end with a flange 40 arranged to enter a slot in the base 10 of the machine and at its outer end with a hand wheel 41 for turning it.

From the above description, it will be evident that the forepart and heel end supporting mem-

bers may be adjusted toward or from each other lengthwise of a shoe to accommodate shoes of different sizes. It will be equally clear that their related positions heightwise of the shoe may be varied to accommodate shoes of different styles, the construction being such as to permit each shoe to be positioned with its waist portion in predetermined relation to a flexible lasting apron 42. This apron, which is preferably made of rubber, extends laterally of the machine above the forepart support 16, and at each side thereof passes over a roll 44 and thence downwardly at each side of the support, each end portion of the apron being clamped between a pair of plates 46. Each pair of plates is pivotally connected at 47 (Fig. 1) to a stud 48 which passes through a lug 50 on the base 10 and has threaded on its outer end a nut 52 engaging the lug 50. By turning the nuts 52, it will be evident that the tension on the apron may be varied at will.

For tipping the block 32 and spindle 33 toward and away from the forepart support, there is provided a hand lever 54 keyed at 56 to a shaft 58 journaled in the heel post 14, the block 32 being also secured to the shaft 58 by a pin 60 (Fig. 2). By this means, when the hand lever 54 is raised, the heel pin will be tipped toward the forepart support 16 to press the forepart of the shoe and the apron 42, which in the illustrated construction extends across the top of the forepart of the shoe between the shoe and the forepart support, firmly down on the forepart support. To lock the heel pin against reverse tipping movement, i. e., in a direction away from the forepart support, and thus to hold the last and shoe firmly in jacked position for the lasting operation, there is provided a ratchet plate 64 secured to the heel post 14. A pawl 66 formed on the end of a pin 68 slidably movable in a bore formed in a boss 62 integral with the hand lever 54 is arranged by engagement with some one of a number of ratchet teeth 63 formed on the ratchet plate to hold the hand lever against downward swinging movement with the heel pin in the position to which it has been tipped in jacking the shoe. Release of the pawl is effected by a thumb lever 70 pivoted in a lug 72 on the hand lever 54 and notched at one end to fit over a screw 74 carried by the pin 68, the boss 62 being slotted to permit movement of the screw 74 and the pin 68 toward and away from the ratchet plate 64. A spring-pressed pin 76 in the hand lever 54 tends normally to urge the thumb lever 70 in a direction to hold the pawl 66 in engagement with one of the ratchet teeth 63. It will be evident that the thumb lever 70 may be pressed in the opposite direction by the operator against the resistance of the spring-pressed pin 76 to withdraw the pawl 66, after which, with the pawl 66 held in withdrawn position, the hand lever 54 and the heel pin may be swung reversely and the last and shoe removed from the shoe supporting means.

In the illustrated embodiment of the invention each of the rolls 44 is mounted on a short shaft 78 carried in a yoke 80 to which is secured a pin 82 journaled for pivotal movement in a bore in a link member 84. Axial movement of the pin 82 in the bore is prevented by a split collar 86 clamped to the pin by means of a screw and integral with a handle 88 keyed at 90 to the pin so that movement of the handle 88 will cause the roll to turn about the axis of the pin 82 which extends in a direction generally height-

wise of the shoe. To provide for heightwise movement of the roll, the link 84 is pivotally connected at 85 to a lever 92 one end of which forms a handle 94 which may be grasped by the operator. The other end of the lever is connected by a pin 96 to a supporting member 98 in such manner that the lever may be swung about the axis of the pin, thereby moving the roll heightwise of the last. It is to be noted that the pivotal connection between the lever 92 and the link 84 permits the roll to be tipped by up and down movement of the handle 88 about an axis extending transversely of the last, this axis in the illustrated embodiment of the invention being the axis of the pivotal connection between the link 84 and the lever 92. An adjustable stop screw 100 threaded through the lever 92 bears against the supporting member 98 and limits the downward movement of the lever 92.

As herein shown, the member 98 is mounted to turn about the axis of a shaft 102 that extends generally heightwise of the shoe. By this means the roll and the apron may be swung inwardly or outwardly as the curvature of the side of the last may require when the roll is being moved heightwise. This also permits the roll to be moved inwardly over the bottom face of the last. The shaft 102 is clamped in a split collar 104 integral with a member 106, heightwise movement of the supporting member 98 being prevented by a washer 108 bearing against a surface of the supporting member 98 and secured to the pin 102 by a screw 110. The member 106 is free to swing about a horizontally extending shaft 112 journaled in ears 114 on the frame.

In the operation of the machine, briefly summarized, the operator, after adjusting the heel end and forepart supports for the size and style of shoe to be operated upon, mounts the last and shoe on the spindle 33. It will be understood that when the shoe is presented to the machine, the shoe materials, comprising an upper U and an insole S will have been previously assembled on the last L and preferably, although not necessarily, pulled over and fastened at the toe end by pulling over tacks. It will also be understood that cement will have been previously applied between the margins of the upper and the margin of the insole along the opposite sides of the waist portion of the shoe. By means of the hand lever 54 the operator tips the last pin forwardly to force the forepart of the shoe into the lasting apron 42 and to clamp the shoe and apron against the forepart support 16. The operator is now free to operate upon one side of the shoe at a time and manipulation of one of the rolls will affect only that portion of the apron between the forepart support and the corresponding end of the apron.

In performing the actual lasting, the operator grips the lever 92 and with its swings the roll and the apron inwardly toward the shoe about the shaft 102 until the apron is pressed tightly against the upper by the roll 44. The roll is then raised by swinging the lever 92 about its pivotal pin 96 to stretch the apron heightwise of the last in a direction substantially normal to that portion of the bottom face of the last that curves downwardly toward the heel end rearwardly of the ball line. During this upward movement the roll and apron are also held in tight engagement with the upper by lateral pressure on the handle 94. The roll is thus caused

to follow the heightwise curvature of the lateral face of the last as it is moved upwardly to stretch the apron, by reason of the fact that it is free to turn about the axis of the pin 82, the operator at the same time turning the member 98 about the axis of the shaft 102 to hold the roll pressed against the apron. As the roll moves over that portion of the lateral face of the last that curves inwardly toward its bottom face, the operator may, by manipulation of the handle 88, turn the roll about the axis of the pin 82 to insure that the roll will move toward the bottom face of the last in a direction substantially normal to its edge curvature. As the roll is moved inwardly over the bottom of the last by 15 further lateral swinging movement of the hand lever 92, the marginal portion of the upper is laid inwardly over the sole S and pressed into position to adhere to the insole, the roll acting through the apron to increase the pressure on the apron on the margin of the upper. It will be understood that as the roll is thus moved inwardly over the insole, the yoke 80 is free to tip about the axis of its pivotal connection to the hand lever 92 to permit the roll to accommodate itself to the heightwise curvature of the bottom face of the insole.

After the marginal portion of the upper has thus been laid inwardly over the insole and pressed into position to adhere to the insole, the pressure of the apron on the overlaid margin may be further increased by downward movement of the hand lever 92 and the marginal portion of the upper thus held in lasted position until the cement has set sufficiently to hold the upper. The roll at that side of the shoe is then returned to its initial position, and the operations above described performed at the opposite side of the shoe. It will be obvious of course that effective use of the apron and rolls is not confined to the manner hereinbefore described but their best use will be dependent to some extent upon the skill and judgment of the operator.

Having thus described my invention what I claim as new and desire to secure by Letters Patent of the United States is:

1. In a lasting machine, the combination of a support for a last and its associated shoe materials, a flexible elastic apron extending across the top of the forepart of the last, and means for stretching the apron heightwise of the last in a direction substantially normal to that portion of the bottom face of the last that curves upwardly toward the heel end, rearwardly of the ball line, and then inwardly over the bottom face of the last at each side in a direction substantially normal to the edge curvature of the last bottom in that location to conform the upper tightly to the contours of the lateral faces of the last and to lay the margin of the upper inwardly over an insole on the bottom face of the last.

2. In a lasting machine, means for supporting a last and its shoe materials, a flexible elastic apron for conforming an upper to the contour of a last by frictional engagement with the upper at opposite sides of the last, and a roll arranged to act through said apron to lay the marginal portion of the upper inwardly over an insole on the last, said roll being mounted to turn about an axis extending generally in a direction heightwise of the last during its inward movement to cause it thus to act on the marginal portion of the upper in a direction substantially normal to

the lengthwise curvature of the edge of the last bottom.

3. In a lasting machine, means for supporting a last and its shoe materials, a flexible elastic apron for conforming an upper to the contour of a last by frictional engagement with the upper at opposite sides of the last, and a roll engaging the apron and movable inwardly over the bottom face of the last to cause the apron to lay the marginal portion of the upper inwardly over an insole on the last, said roll being mounted to turn about an axis heightwise of the last to accommodate itself to the lengthwise curvature of the edge of the last bottom; and means for thus turning said roll.

4. In a lasting machine, means for supporting a last and its shoe materials, a flexible elastic apron for conforming an upper to the contour of a last by frictional engagement with the upper at opposite sides of the last, and a roll engaging the apron and movable inwardly over the bottom face of the last to cause the apron to lay the marginal portion of the upper inwardly over an insole on the last, said roll being mounted to turn about an axis extending heightwise of the last to accommodate itself to the lengthwise curvature of the edge of the last bottom and to tip about an axis extending transversely of said last to accommodate itself to the heightwise curvature of the bottom face of the last.

5. In a lasting machine, means for supporting a last and its shoe materials, a flexible elastic apron arranged to extend across the top of the forepart of the last, means for securing the opposite end portions of the apron at opposite sides of the last and below its bottom face, devices arranged to engage the apron at the opposite sides of the last between the last and the ends of the apron, and means for moving said devices relatively to said securing means heightwise of the last in a direction substantially normal to that portion of the bottom face of the last that curves upwardly toward the heel end rearwardly of the ball line and then inwardly over its bottom face in directions substantially normal to the edge contour of the last bottom in that location to cause the apron to conform the upper tightly to the contours of the opposite lateral faces of the last and to lay the marginal portions of the upper inwardly over an insole on the last.

6. In a lasting machine, means for supporting a last and its shoe materials, a flexible elastic apron arranged to extend across the top of the forepart of the last, means for securing the opposite end portions of the apron at opposite sides of the last, and rolls arranged to engage the apron at the opposite sides of the last between the last and the ends of the apron and by movement heightwise of the last and inwardly over its bottom face to stretch the apron about the last and to cause it to conform the upper tightly to the heightwise curvatures of the lateral faces of the last and to lay its marginal portion inwardly over an insole on the last, each of said rolls being mounted to turn about an axis extending generally heightwise of the last to permit the roll to accommodate itself to the lengthwise curvature of the edge of the last bottom in laying the marginal portion of the upper through the apron inwardly over the insole.

7. In a lasting machine, means for supporting a last and its shoe materials, a flexible elastic apron for conforming an upper to the contour of the last by frictional engagement with the upper at opposite sides of the last, a pair of rolls

at opposite sides of the last, manually-operated means for moving said rolls in directions heightwise of the last and inwardly over its bottom face to stretch the apron about the last and to cause it to conform the upper tightly to the heightwise curvatures of the lateral faces of the last and to lay its marginal portion inwardly over an insole on the last, and means enabling the operator to turn said rolls about axes extending generally heightwise of the last during their inward movement to cause the rolls to move inwardly over the bottom of the last in directions substantially normal to the edge curvatures of the last bottom.

8. In a lasting machine, means for supporting a last and its shoe materials, a flexible elastic apron for conforming an upper to the contour of a last by frictional engagement with the upper at opposite sides of the last, and rolls at opposite sides of the last, said rolls being mounted for bodily swinging movements about different axes adjacent one end of the last and extending heightwise and transversely of the last, said rolls being arranged to act through the apron to hold the upper in intimate contact with the sides of the last while stretching the apron about the last to cause the apron to conform the upper tightly to the heightwise curvatures of the lateral faces of the last and to lay its marginal portion inwardly over an insole on the last.

9. In a lasting machine, means for supporting a shoe at the heel end and at the forepart, a flexible elastic apron arranged to extend across the top of the forepart of the shoe in position to be clamped between the shoe and said supporting means, means for securing the opposite end portions of the apron at opposite sides of the last, and devices for engaging the apron and for pressing it against the opposite sides of the shoe,

said devices being mounted for bodily movements heightwise of the last and inwardly over its bottom face thereby to stretch the apron to cause it by frictional contact with the upper to work the upper into tight conformity to the heightwise curvatures of the lateral faces of the last and to lay its marginal portions inwardly over an insole on the last, said devices being also mounted for free turning movement about axes extending heightwise of the last to maintain the proper lateral pressure on the apron and to move inwardly over the bottom face of the last in directions substantially normal to the edge curvatures thereof.

10. In a lasting machine, means for supporting a last and its shoe materials, said means comprising a forepart support and a heel pin mounted for tipping movements in directions toward and from said forepart support, a flexible elastic apron arranged to extend across the top of the forepart of the last in position to be clamped between the forepart support and the shoe in response to the tipping of said heel pin toward the forepart support, means for locking the heel pin against tipping movement in a direction away from said forepart support, means for securing the opposite end portions of the apron at opposite sides of the last, and devices arranged to engage the apron at the opposite sides of the last between the shoe and the ends of the apron, and by movement relative to said securing means heightwise of the last and inwardly over its bottom face to stretch the apron about the last to cause it to conform the upper tightly to the heightwise curvatures of the lateral faces of the last and to lay its marginal portion inwardly over an insole on the last.

JOHN T. LANCASTER.
